UNITED STATES PATENT OFFICE.

PERLEY R. GLASS, OF BROOKLINE, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,312,532.

Specification of Letters Patent.

Patented Aug. 12, 1919.

Application filed November 1, 1918. Serial No. 280,732.

To all whom it may concern:

Be it known that I, PERLEY R. GLASS, a citizen of the United States, residing at Brookline, in the county of Norfolk and 5 State of Massachusetts, have invented certain Improvements in Folding-Machines, of which the following description, in connection with the accompanying drawings, is a specification, like reference characters on the 10 drawings indicating like parts in the several figures.

This invention relates to folding' machines and is herein illustrated as embodied in a machine for folding the margin of a 15 closed vamp.

Machines for performing this operation have been provided with two horizontally extending arms, a work-supporting arm located in position to permit a closed vamp 20 to be fed around it and an arm overhanging the work-supporting arm, the driven members which feed the vamp, snip the margin thereof and press the fold together with mechanisms for driving them being mounted partly on the overhanging arm and partly 25 on the work-supporting arm. These driven members and their operating mechanisms occupy more or less space, and the mounting of part of them upon the work-supporting 30 arm limits the extent to which the size of that arm may be reduced. It is desirable, however, that the cross-sectional dimensions of the work-supporting arm be made as small as possible so as to facilitate the folding 35 of vamps having narrow throats, but in the prior machines it has not been possible to reduce the size of the work-supporting arm to the desired extent because of the necessity for providing space for some 40 driven member, for example the fold-presser and its driving mechanism.

According to one feature of the present invention the driven members which engage the vamp are all mounted on an overhanging arm, such construction permitting the work support to be made of small cross-section so that vamps having narrow throats may readily be operated upon.

This and other features of the invention, 45 including certain details of construction and combinations of parts, will be described as

embodied in an illustrative machine and pointed out in the appended claims.

Referring now to the accompanying drawings,—

Figure 1 is an elevation of a machine in which the present invention is embodied, and

Fig. 2 is a detail perspective showing the mounting of the fold-presser and plow.

The illustrative machine is an improvement upon the machine of application Serial No. 5245 filed in my name. Projecting horizontally from the frame 2 of the machine and located so as to permit a closed vamp to be fed around it is a work-supporting arm 1 of small cross-section; and located above this is an overhanging arm 5. Mounted in the overhanging arm is a driving shaft 4 which may be rotated through any suitable clutch mechanism (not shown). This arm carries a snipping knife 104, a presser-foot 92, and a feeding foot 24. The feeding foot is carried by a rod 36 mounted in a sleeve 38 the stem of which is pivotally held in a slide 48, said slide being connected by a link 52 with a bell-crank spacing lever 54 movement of which about the shaft 115 raises or lowers the slide 48 and thereby the pivot about which the foot 24 oscillates. The stem 80 of the feeding foot 24 is oscillated and also raised and lowered by a cam (not shown), on the shaft 4 which rotates in a cam-follower carried at the upper end of the stem. The stem 96 of the presser foot 92 is reciprocated by a second cam on the shaft 4 which engages a second cam-follower 98 on the upper end of the stem 96. The knife 104 is normally inoperative but may be rendered operative at any time by moving the rod 112 to the left and thereby moving a hook-shaped piece 108 between a shoulder on the cam-follower 98 and a pin 109, said hook-shaped piece being suitably connected with the knife. A link 86 connected at one 95 end to a treadle-controlled bell-crank lever 66 is connected at the other end at 114 to an arm fast to the farther end of the shaft 115, the rod 112 being yieldingly connected with said arm. A second arm 116 fast to the 100 nearer end of the shaft 115 is provided with a locking pin, the head of which is shown

- at 118; and this pin may be caused to enter any one of a number of holes 119 formed in an enlargement on the lever 54, or the pin may be locked in inoperative position.
- 5 When the arm 116 is locked to the lever 54, a downward pull on the treadle rod will simultaneously throw in the knife and decrease the extent of the intermittent feeds caused by the movements of the feed foot 24.
- 10 When the arm 116 is not locked to the lever 54, a downward pull on the rod 68 will throw in the knife without affecting the extent of the intermittent feed movements. Pivoted on the work-supporting arm 1 and adapted to
- 15 coöperate with the feeding-foot 24 is an oscillating block 26 the upper edge of which passes through a slot in a plate 8. This block is angularly movable about the axis of the screw 27 and is normally held in rearward position with reference to the feed movement of the work by a spring (not shown) but swings forwardly with the feeding-foot and the stock during each intermittent forward movement of said foot. An
- 20 anvil 20, mounted on the plate 8, supports the work during the pressing of the fold; and a gage 12 and plow 125, the former mounted on the plate 8, serve respectively to guide the work by engagement with its
- 25 edge and to form the fold.

30 The construction which has been thus briefly outlined with the exception of the work-supporting arm 1 and the mounting of the plow 125, is or may be the same as that of the machine of the application and will not be described further in detail.

35 In the machine of the prior application the hammer or fold-presser is mounted on a lower arm which corresponds to the arm 1 and the actuating mechanism for the fold-presser passes through the arm. With such a construction the extent to which the size of the arm may be reduced is limited by the presence of the fold-presser and its actuating mechanism. It is desirable on the other hand to make the cross-sectional dimension of this arm as small as is possible compatible with rigidity so that when a

40 vamp having a narrow throat is being operated upon the vamp may be turned readily about the arm without engaging the sides of the arm if possible, and without stretching the throat of the vamp. Consequently any construction which permits the cross-sectional dimension of the arm to be decreased within reasonable limits tends to improve the work turned out by the machine.

45 In the present machine no driven parts whatever are mounted in or on the work-supporting arm. As has been explained above, the presser-foot, feeding-foot and knife as well as their actuating mechanism are mounted on the overhanging arm 5. In addition the fold-presser of the present machine is also mounted upon the same arm.

50 Referring more particularly to Fig. 2, the fold-presser 101, the operative face of which is inclined complementally to the incline of the face of the anvil 20 is carried at one end of a link 103 the other end of which is pivoted at 105 to one end of a lever 107, said lever being pivoted at 109 to a stationary part of the machine and at 111 to a rod 113 having at its upper end an eccentric strap which encircles an eccentric on the driving 55 shaft 4. A bracket 215 fastened to the arm 5 has pivoted between its arms at 117 one end of a link 119 the other end of which is pivoted at 121 to the link 103 which carries the fold-presser 101. With this construction, 60 rotation of the shaft 4 causes vibration of the fold-presser toward and from the anvil to press the fold. The linkage which has been described imparts to the fold-presser during its downward movement a 65 movement to the left or inwardly with respect to the work, that is, a movement from the edge of the fold toward the body portion of the work. The purpose of imparting to the fold-presser this compound downward and inward movement is to lay the fold properly and to insure that the edge of the finished fold shall be a smooth curve. All of the driven members for engaging the work are thus mounted on the overhanging 70 arm, and the work-supporting arm may be made of as small cross-sectional dimensions as is consistent with proper rigidity of said arm. Moreover, the present construction permits the employment of the improved 75 mechanism for operating the fold-presser, 80 a construction which would not be permissible if the fold presser were mounted on the work-supporting arm because of the space which said mechanism would occupy. 85

90 The folder 125, herein shown as a stationary plow, is formed at the lower end of an arm 127 which is fastened at its upper end by a screw 129 to the bracket 215 and is thus carried by the overhanging arm 5.

95 The operation of the machine is as follows:—The presser-foot is raised by manipulating a finger-lever 102, and the inner margin of the vamp placed against the gage 12, the arm extending into the opening in the vamp and the vamp being suspended on the arm with the greater portion of the vamp hanging down below the level of the arm. Power is then applied to the shaft 4, the vamp being fed intermittently by the action of the feeding-foot 24 and the presser-foot 92. As the margin progressively encounters the curved face of the folder 125 a fold is formed, and this fold is subsequently pressed by the fold-presser 101. The inner margin of the closed vamp is thus operated upon until the starting point has been reached again and the entire margin has been folded. During the folding of the throat it is usually desirable to throw in the snipping knife and decrease 100

the rate of feed, both of which may be accomplished by operating a treadle (not shown) which is attached to the treadle rod 68.

5 Although the invention has been set forth as embodied in a particular machine in which the work is supported on the end of a substantially horizontal arm, it should be understood that the invention is not 10 limited in the scope of its application to the particular machine which has been described.

Having thus described my invention, what I claim as new and desire to secure by Letters Patent of the United States is:

15 1. A folding machine, having in combination, a work-supporting arm of small cross-section adapted to enter the opening in a closed vamp and to permit the vamp 20 to be fed along the supporting face thereof, driven members for engaging the vamp, mechanism for driving said members, and means independent of the work-supporting arm upon which all of said members and 25 mechanisms are mounted.

2. A folding machine, having in combination, a work-support of small cross-section adapted to enter the opening in a closed vamp and to permit the vamp to be fed 30 over the supporting face thereof, an arm having its free end in proximity to said supporting face, means for feeding the vamp, means for folding the margin thereof, and means for pressing the fold, said 35 last-named means including a fold-presser mounted on the arm.

3. A folding machine, having in combination, a work-support of small cross-section adapted to enter the opening in a closed 40 vamp and to permit the vamp to be fed over the supporting face thereof, an arm having its free end in proximity to said supporting face, means for feeding the vamp, means for folding the margin thereof, and means for pressing the fold, said 45 last-named means including a fold presser and operating means therefor mounted on the arm.

4. A folding machine, having in combination, a frame having a work-supporting 50 arm of small cross-section projecting therefrom in position to permit a closed vamp to be passed around said arm and a second arm overhanging the first-named arm, and 55 feeding, folding and fold - pressing members mounted on the adjacent ends of said arms and including a fold - pressing member mounted on the overhanging arm.

5. A folding machine, having in combination, a frame having a work-supporting 60 arm of small cross-section projecting therefrom in position to permit a closed vamp to be passed around said arm and a second arm overhanging the first-named arm, means 65 for feeding the vamp, means for forming a

fold in the margin thereof, and means for pressing the fold, said feeding and fold-pressing means being mounted on the overhanging arm.

6. A folding machine, having in combination, a frame having a work-supporting 70 arm of small cross-section projecting therefrom in position to permit a closed vamp to be passed around said arm and a second arm overhanging the first-named arm, and 75 feeding, folding and fold-pressing members mounted on the overhanging arm.

7. A folding machine, having in combination, a frame having a work-supporting 80 arm of small cross-section projecting therefrom at a height sufficient to permit a closed vamp to be passed around said arm and a second arm overhanging the first-named arm, and feeding, folding and fold-pressing members mounted on the overhanging arm. 85

8. A folding machine, having in combination, a frame having a work-supporting arm of small cross-section projecting therefrom at a height sufficient to permit a closed vamp to be passed around said arm and a 90 second arm overhanging the first-named arm, and feeding, snipping, folding and fold-pressing members mounted on the overhanging arm.

9. A folding machine, having in combination, a frame having a work-supporting 95 arm of small cross-section projecting therefrom at a height sufficient to permit a closed vamp to be passed around said arm and a second arm overhanging the first-named 100 arm, feeding, folding and fold-pressing members mounted on the overhanging arm, and operating mechanism for the feed member and the fold-pressing member also mounted on the overhanging arm. 105

10. A folding machine, having in combination, a frame comprising a work-supporting portion and an overhanging arm, and a feed member, a stationary folder and a fold-presser all mounted on said arm. 110

11. A folding machine, having in combination, a support for the work, means for feeding the work and forming a fold in the margin thereof, a fold-presser, means for vibrating the fold-presser, and a link pivoted to the fold-presser and to a stationary part of the frame, said link serving to control the direction of movement of the fold-presser. 115

12. A folding machine, having in combination, a support for the work, means for feeding the work and for forming a fold in the margin thereof, a fold-presser, means for vibrating the fold-presser, and a guiding link pivoted at separated points respectively to the fold-presser and to the frame of the machine, the link and the pivots being located to move the fold-presser in a direction transverse to the folded margin and toward the unfolded portion of the 120 125 130

work during the pressing movement of the fold-presser.

13. A folding machine, having in combination, a support for the work, means for feeding the work and for forming a fold in the margin thereof, a fold-presser, means for vibrating the fold-presser, and a guiding link pivoted at separated points respec-

tively to the fold-presser and to the frame of the machine, the pivot which connects 10 the link to the fold-presser being located above the pivot which connects the link to the frame.

In testimony whereof I have signed my name to this specification.

PERLEY R. GLASS.
